UNITED STATES PATENT OFFICE.

CORNELIUS V. COLL AND THOMAS A. COLL, OF VICTOR, COLORADO.

DUST CAP FOR AUTOMOBILES.

Application filed June 2, 1925. Serial No. 34,410.

To all whom it may concern:

Be it known that we, CORNELIUS V. COLL and THOMAS A. COLL, citizens of the United States, residing at Victor, in the county of 5 Teller and State of Colorado, have invented certain new and useful Improvements in Dust Caps for Automobiles; and we do hereby declare the following to be a full, clear, and exact description of the invention, 10 such as will enable others skilled in the art to which it appertains to make and use the same.

This invention relates to dust caps for the valve stems of pneumatic tires, and has for 15 one of its objects to improve the general construction of articles of this character and to provide one that shall embody a retaining section adapted to be threadedly connected to the valve stem, a closure section adapted 20 to be easily and quickly slipped onto and off of the retaining section, and means carried by the closure section and engaging the valve stem to prevent the accidental displacement of said closure section.

25 The invention consists of the construction, combination and arrangement of parts hereinafter fully described and claimed, and illustrated in the accompanying drawing, wherein:

30 Figure 1 is an elevational view of the dust cap supplied to a valve stem,

Figure 2 is a longitudinal sectional view of the valve stem and dust cap taken on the plane indicated by the line 2—2 of Figure 1,

35 Figure 3 is a longitudinal sectional view of the dust cap with the closure section in partly opened position, and

Figure 4 is a similar view with the closure section in fully opened position.

40 Corresponding and like parts are referred to in the following description, and designated in the several views of the accompanying drawing, by similar reference characters.

45 In the drawing 1 designates a valve stem for pneumatic tires and as shown includes a threaded body portion 2 provided at its inner end with a threaded nipple 3.

50 The retaining section 4 of the dust cap is provided at one end with an integrally formed rim nut 5 by means of which it is removably secured to the body portion 2 of the valve stem 1. The rim nut 5 has an annular recess 6 in which is seated a packing ring 7 for contact with the inner side of the wheel rim through which the valve stem 1 passes. The section 4 above the nut 5 has an

internal transverse dimension greater than the external diameter of the body 2 of the valve stem 1, and is provided with opposed longitudinally extending slots 8 having inclined end walls 8^a. This section is provided in its outer side with grooves 9 registering with the slots 8.

The closure section 10 of the dust cap has a snug sliding fit on the retaining section 4. 60 One end of the section 10 is closed by a wall 11, and secured within this section are leaf springs 12. The springs 12 are arranged directly opposite each other and extend longitudinally beyond the open end of the section 10. The springs 12 extend into the section 4 through the openings 8, and are provided at their free ends with heads 13 which when the section 10 is in closed position contact with the body portion 2 of the valve 70 stem 1 and due thereto prevent this section from casually moving into opened position. The heads 13 are held in contact with the body portion 2 of the valve stem 1 by shanks 14 through the medium of which they are 75 secured to the springs 12 and which when the section 10 is in closed position contact with the inner surface of the section 4. The grooves 9 are provided for the purpose of receiving the upper end portions of the springs 12 when the section 10 is in closed position. The springs 12 are under tension 80 when the section 10 is in closed position, and react and move the shanks 14 into the slots 8 when this section is in the partly 85 opened position shown in Figure 3. The shanks 14 are round so as to permit the section 10 to be swung from its partly opened position to the fully opened position shown in Figure 4. To return the section 10 to 90 closed position it is only necessary to first move it into partly opened position and then slide it onto the section 4. To direct the free ends of the springs 12 into the section 4 while the section 10 is being slid onto this 95 section, the shanks 14 are provided with beveled portions 15 for cooperation with the beveled end walls 8^a of the slots 8.

A rod 16 passes freely through an opening 17 in the end wall 11 of the section 10, and is provided with an air cap 18 having threaded engagement with the nipple 3 of the valve stem 1. The rod 16 is provided with a knurled head 19 by which it may be turned to apply the air cap 18 to or remove it from the nipple 3 of the valve stem 1.

Whenever it is desired to inflate the tire

of which the valve stem 1 forms a part, the section 10 is withdrawn from the section 4 and thence swung into an angular position with respect thereto and this may be readily done after disengaging the air cap 18 from the nipple 3 of the valve stem 1. After the tire has been inflated the section 10 is again applied to the section 4 and after this has been done the air cap 18 is threaded onto the nipple 3 of the valve stem 1. As the heads 13 are held in frictional contact with the body portion 2 of the valve stem 1 by the springs 12, the section 10 is held against casual movement into opened position.

15 It should be understood that the drawing is merely illustrative and does not pretend to give exact proportions. Furthermore, the said drawing is illustrative of a preferred construction, it being our expectation that various changes and modifications may be made within the scope of the claims without departing from the spirit and scope of our invention.

What is claimed is:—

25 1. A dust cap for a valve stem, comprising a retaining section adapted for threaded engagement with the valve stem and provided with slots, a closure section slidably mounted on the retaining section, springs carried by the closure section and entering the retaining section through the slots, and elements carried by the springs for frictional engagement with the valve stem.

35 2. A dust cap for a valve stem, comprising a retaining section provided with longitudinally extending slots having their inner end walls beveled, a closure section removably applied to the retaining section, springs carried by the closure section and entering the retaining section when the closure section is applied to the retaining section, said springs being adapted to occupy a position exteriorly of the retaining section when the closure section is removed from the retaining section, shanks carried by said springs and adapted to extend through said slots when the closure section is removed from

the retaining section, said shanks having beveled portions adapted to cooperate with the beveled walls of said slots to direct the inner ends of the springs into the retaining section during the application of the closure section to the retaining section, and elements carried by said shanks for engagement with the valve stem when the closure section is applied to the retaining section.

3. A dust cap for a valve stem, comprising a retaining section adapted for threaded engagement with the valve stem, a closure section slidably mounted on the retaining section, and an air cap slidably and rotatably carried by the closure section.

4. A dust cap for a valve stem, comprising a retaining section provided with slots, a closure section slidably mounted on the retaining section, springs carried by the closure section and entering the retaining section through the slots, and elements carried by the springs for engagement with the valve stem.

5. A dust cap for a valve stem, comprising a retaining section, a closure section removably applied to the retaining section, and means carried by the closure section and adapted to releasably engage the valve stem when the closure section is applied to the retaining section and adapted to pivotally connect the closure section to the retaining section when the closure section is removed from the retaining section.

6. A dust cap for a valve stem, comprising a retaining section, a closure section removably applied to the retaining section, and means adapted to establish a releasable connection between the closure section and the valve stem when said section is applied to the retaining section and adapted to pivotally connect the closure section to the retaining section when the former section is withdrawn from the latter.

In testimony whereof we affix our signatures.

CORNELIUS V. COLL.
THOMAS A. COLL.
